UNITED STATES PATENT OFFICE.

EDWARD WOTTON, OF EDGEWATER, NEW JERSEY.

DISPLAY SIGN FOR PASSENGER VEHICLES.

Application filed December 10, 1921. Serial No. 521,282.

To all whom it may concern:

Be it known that I, EDWARD WOTTON, a citizen of the United States, residing at Edgewater, in the county of Bergen and State of New Jersey, have invented certain new and useful Improvements in Display Signs for Passenger Vehicles, of which the following is a specification, reference being had therein to the accompanying drawing.

10 This invention relates to display signs for advertising purposes for use in connection with passenger vehicles, and more particularly in connection with motor buses of the type in which an upper deck is provided for 15 the accommodation of passengers. In certain types of such buses, the destination sign is sustained at the front of the bus body which sign is pervious to light and is illuminated by a lamp situated in rear of the 20 sign. In accordance with the present invention, an advertising sign is provided which is located above the destination sign and faces to the rear so that it can be read from the deck of the bus, the said sign being so 25 positioned with reference to the said lamp that it will be illuminated by the light from the same, with the result that the advertising matter on the sign will be conspicuously displayed to the vision of passengers occupying the deck.

In the accompanying drawings:

Fig. 1 is a longitudinal section through the front of the upper portion of a bus on the line *a—a* of Fig. 2 having my invention applied thereto.

Fig. 2 is a front elevation of the same.

Fig. 3 is an elevation of the front end of the deck as viewed from the rear and showing the rearwardly facing advertising sign.

40 Referring to the drawings:

1 designates the bus body and 2 the upper passenger deck, which is enclosed as usual by the side walls 3 and the front wall 4, which walls are surmounted by the usual 45 side railings 5 and front railing 6. 7 designates a destination sign which is sustained by the bus body in front of the wall 4 and is preferably pervious to light and illuminated from the rear by lamps 8 sustained between 50 the wall and the sign. Due to this construction the sign can be read from in front of the bus, and the lamp will be hidden by the wall 4 from the direct view of the passengers occupying the deck.

55 9 designates an advertising display sign

which is sustained by the bus body above the destination sign and above the front wall 4, the said advertising sign facing to the rear so that it can be observed by the passengers on the deck. To support this sign a panel 10 is provided which extends upwardly and rearwardly from a point above the destination sign and is connected at its upper portion to the front railing 6. The panel is provided with a horizontal bead 11 at about the 60 level of the upper edge of the wall 4 which bead is formed with a groove 12 to receive the lower edge of the sign whose upper edge is seated in a groove in a horizontal bead 13 at the upper edge of the panel. Thus arranged, the sign will be exposed to the direct rays of the light from the lamp 8 and will be illuminated thereby, so that it will be plainly visible and can be clearly read by the passengers on the deck. A horizontal transparent panel 14 extends vertically upward from the top of the wall 4 to the railing 6 and protects the sign 9, the said panel being hinged to the wall by hinges 15 so that it can be swung downwardly and rearwardly 65 to permit access to the sign. By locating the advertising sign in the position described, where it can be viewed by the passengers on the deck facing the front, and where it will be illuminated by the lamp which illuminates the destination sign, the advertising sign will be brought out in conspicuous relief and will attract the attention of the passengers and thus serve to bring prominently 70 to their attention the advertising matter 75 80 85 90 95 100 105 110

In the foregoing description and accompanying drawings I have set forth my invention in the particular detailed form and arrangement of the parts which I prefer to adopt but it will be understood that these details may be variously changed and modified without departing from the limits of the invention; and further it will be understood that the invention is not limited to any particular form or construction of the parts except in so far as such limitations are specified in the claims.

Having thus described my invention, what I claim is:

1. In a combination with a bus body having an upper passenger deck, a destination sign pervious to light supported at the front of the body adjacent the level of the deck, a lamp in rear of said sign to illum- 110

nate it so that it can be read from in front of the bus, and an advertising sign supported above and in front of the deck and facing to the rear to be read from the deck, 5 said advertising sign being exposed to the direct rays of said lamp so as to be illuminated thereby.

2. In combination with a bus body having an upper passenger deck provided with 10 a front wall, a destination sign pervious to light sustained in front of said wall, a lamp between the wall and destination sign to illuminate the latter so that it can be read from in front of the bus, and an advertising sign sustained above the wall forward of the same and facing to the rear to be read from the deck, said advertising sign being in position to be illuminated by the direct rays of said lamp.

20 3. In combination with a bus body having an upper passenger deck provided with a front wall, and with a front railing above the wall, a destination sign pervious to light sustained by the body in front of said wall, 25 a lamp between the wall and sign to illuminate it so that it can be read from in front

of the bus, a panel extending upwardly and rearwardly from the top of the sign and connected with said railing, and an advertising sign applied to the rear face of the 30 panel to be read from the deck, said sign being in position to be illuminated by said lamp.

4. In combination with a bus body having an upper passenger deck provided with 35 a front wall and with a front railing above the wall, a destination sign pervious to light sustained by the body in front of said wall, a lamp between the wall and sign to illuminate the latter, a panel extending upwardly 40 from the destination sign and connected with said railing, an advertising sign applied to the rear face of the panel to be read from the deck, said sign being in position to be illuminated by said lamp, and 45 a transparent panel in rear of said advertising sign between the top of the wall and railing.

In testimony whereof, I have affixed my signature hereto.

EDWARD WOTTON
